Primary Examiner—Terry A Wallace*(74) Attorney, Agent, or Firm*—Neal, Gerber & Eisenberg
LLP(57) **CLAIM**

The ornamental design for measuring cups, as shown and described.

DESCRIPTION

FIG. 1 is a perspective view of the measuring cups of the present invention, including a leveler;

FIG. 2 is a side elevational view of the measuring cups as shown in FIG. 1;

FIG. 3 is a side elevational view of the measuring cups as shown in FIG. 1, from the opposite side of FIG. 1;

FIG. 4 is a top plan view of the measuring cups as shown in FIG. 1;

FIG. 5 is a bottom plan view of the measuring cups as shown in FIG. 1;

FIG. 6 is a front elevational view of the measuring cups as shown in FIG. 1; and,

FIG. 7 is a rear elevational view of the measuring cups as shown in FIG. 1.
